United States Patent Office.

G. W. N. YOST, OF CORRY, PENNSYLVANIA, ASSIGNOR TO CORRY MACHINE COMPANY, OF SAME PLACE.

Letters Patent No. 78,712, dated June 9, 1868.

IMPROVEMENT IN MOWING-MACHINES.

The Schedule referred to in these Letters Patent and making part of the same.

TO ALL WHOM IT MAY CONCERN:

Be it known that I, G. W. N. Yost, of Corry, Erie county, in the State of Pennsylvania, have invented certain new and useful Improvements in Mowing-Machines; and I do hereby declare that the following is a full and exact description thereof, reference being had to the accompanying drawings, making part of this application.

My invention relates to certain new and useful improvements in mowing-machines, and has for its main object the production of an exceedingly simple and economic mode of construction, in which the finger-bar will remain upon and adapt itself to the uneven surfaces over which it may pass, while the wheels of the machine are in various positions relatively to the cutting-apparatus, and in which the entire cutting-apparatus may be lifted up at the pleasure of the operator (or driver) by a simple device, without in the least changing the relative positions of the cutter-driving mechanism, or interfering with its operations.

And to these ends my invention consists in hanging the vibratory or swinging finger-bar holder upon the crank-shaft, whereby I am enabled to vibrate or swing said holder-bar (to throw up or drive the whole cutting-apparatus) without changing the relative positions of the parts of the cutter-mechanism and the driving-crank, as will be presently more fully explained.

To enable those skilled in the art to make and use my invention, I will proceed to describe more fully the construction and operation of one of my improved machines, referring by letters to the accompanying drawings, in which—

Figure 1 is a top view,

Figure 2 a side elevation, and

Figure 3 a front view of the same.

In the several figures the same letters of reference denote the same parts of this machine.

A A are the main ground and driving-wheels, which are mounted to turn freely in the usual way on the axle B, and which are provided with internal driving-gears, C C, which engage with and drive respectively two pinions, d d, on the ends of the main driving-shaft E.

On this shaft, near its centre, is keyed a bevel-gear, F, which drives the bevel-pinion g on the rear end of the counter-shaft H, and this shaft carries, at its forward end, the face-plate i, in which is the crank-pin K, to which is connected one end of a pitman, L, which is coupled at its other end by a pin, m, to one end of cutter-bar N, and by which said cutter-bar is driven in the usual way.

O is the finger-bar, p the fingers, and Q is the swinging or vibratory holder-bar, to the lower end of which is hung, at r, the finger-bar, as clearly shown.

This holder-bar Q is hung on the forward portion of the crank-shaft H, with a suitable box or bearing arranged between the front edge of frame I of the machine and the crank-wheel i, as clearly shown in the drawing, and said holder-bar Q turns freely (as upon a pivot) on said shaft.

S is a toothed segment secured to the frame I, and having its teeth arranged in the arc of a circle, the centre of which is coincident with centre of shaft H, (on which bar Q turns,) so that a spur-pinion, T, hung at the end of bar Q, will work freely in said segment S. This pion is hung to turn freely on the inner end of a stud secured fast to the end of bar Q, and to the outer end of said stud is fastened the lower end of a handle or bar, U, which is worked by the driver, and by means of which the said bar Q (through the medium of pinion T and segment S) is vibrated to throw up and let down the cutting-apparatus of the machine.

This device or means of effectually placing within reach and ready control of the driver the cutting-apparatus, so that he can raise and lower it at will, I deem simple and practical, but of course some other means might be devised and employed without departing from my invention in other particulars.

The boxes for the bearings of the main and counter-shafts I propose to cast in or on the frame I, and bush

them with suitable brass or other linings or bearings, and may be formed with suitable oil-reservoirs for the lubrication of the journals.

P is the tongue and W the driver's seat. The latter is mounted over the rear portion of the frame of the machine by means of a stand, t, secured by a bolt to said frame, and the tongue is also bolted to said frame, and secured to the axle, as clearly shown.

I propose to cast in the frame the two bolts for effecting the fastening of the tongue and seat, so that in applying the seat and tongue it may be necessary only to put these parts in place, and screw on the necessary nuts.

It will be seen that making the frame of the machine substantially as shown, and arranging therewith the shafts and other main parts, as described, the machine is rendered exceedingly light, simple, and economic of construction, while at the same time it is fully efficient and durable. And it will also be observed that by the employment of the swinging bar Q, arranged to turn upon the shaft H, which carries the crank-plate, the raising and lowering of the cutting-apparatus by means of said, or in conjunction with said bar, may be accomplished readily without changing the relations of the parts of the cutter and cutter-driving mechanisms.

In fig. 3, I have illustrated in red lines the different conditions of the wheels and frame of the machine, (in consequence of the wheels passing over elevations,) which may exist without changing the position of the cutting-mechanism, and the entire lifting of the cutting-apparatus, by means of the lever worked by the driver, will be readily comprehended by those familiar with this kind of machinery.

After what has already been said of the construction, arrangement, and separate operations of the several parts, the general operation of the machine will be readily understood. The main wheels, with their internal gears, drive the main shaft through the medium of its pinions, and it in turn imparts motion through the bevel-gear and pinion to the crank-shaft, which, by means of the crank and pitman, drives the cutter-bar in the usual manner.

Having fully explained my improved machine, so that those skilled in the art can make and use the same, what I claim therein as new, and desire to secure by Letters Patent, is—

Hanging or pivoting the vibratory lifting-bar Q upon the crank-shaft, substantially as and for the purpose set forth.

I also claim, in combination with the vibratory or lifting-bar Q, the stationary segment, travelling-pinion and hand-lever, or its equivalent, by means of which the said bar Q may be readily manipulated by the driver, which at the same time it is free to move, as required, when not controlled by him, substantially as described.

In testimony whereof, I have hereunto set my hand and seal, this twenty-second day of November, 1867.

G. W. N. YOST. [L. S.]
